UNITED STATES PATENT OFFICE.

MAUDE LILLIAN DE BRETEVILLE, OF CORONADO, CALIFORNIA.

DESIGN FOR A TOY ANIMAL.

Application filed December 27, 1927. Serial No. 24,673. Term of patent 14 years.

To all whom it may concern:

Be it known that I, MAUDE LILLIAN DE BRETEVILLE, a citizen of the United States, residing at Coronado, in the county of San Diego and State of California, have invented a new, original, and ornamental Design for a Toy Animal, of which the following is a specification, reference being had to the accompanying drawing, forming a part thereof, in which the figure is a perspective view of a toy animal showing my new design.

I claim:

The ornamental design for a toy animal, substantially as shown.

In testimony whereof, I have hereunto set my hand at San Diego, California, this 15th day of December, 1927.

MAUDE LILLIAN DE BRETEVILLE.
